UNITED STATES PATENT OFFICE.

MAX MAXIMILIAN, OF BUFFALO, NEW YORK.

PNEUMATIC HAMMER.

SPECIFICATION forming part of Letters Patent No. 776,671, dated December 6, 1904.

Application filed April 13, 1904. Serial No. 202,902. (No model.)

To all whom it may concern:

Be it known that I, MAX MAXIMILIAN, a subject of the Emperor of Germany, residing at Buffalo, in the county of Erie and State of New York, have invented new and useful Improvements in Pneumatic Hammers, of which the following is a specification.

This invention relates to pneumatic hammers of that class in which the reversing-valve moves axially with reference to the piston.

The objects of this invention are to improve the construction of the reversing-valve mechanism, so as to increase the number of strokes of the piston within a given time and to permit of making repairs easily and also to provide simple and efficient means for automatically lubricating the working parts of the hammer.

In the accompanying drawings, consisting of two sheets, Figure 1 is a longitudinal section of my improved pneumatic hammer, the ports and passages being shown diagrammatically for convenience in illustrating the invention. Fig. 2 is a fragmentary view similar to Fig. 1, showing the reversing-valve in a shifted position. Figs. 3 and 4 are cross-sections in lines 3 3 and 4 4, Figs. 1 and 2, respectively.

Similar letters of reference indicate corresponding parts throughout the several views.

A represents the main or power cylinder of the hammer; B, the piston reciprocating therein; C, the tool or die fitted in the lower or rear end of the cylinder; D D', the front and rear sections of the reversing-valve chest mounted on the front end of the cylinder; E, the head or cap inclosing the valve-chest and having a screw connection with the cylinder, and F the handle applied to the outer side of the cap. Above the upper section of the valve-chest the cap is provided with an air-distributing chamber G, and the handle is provided with a passage g, which connects the distributing-chamber with a tube or other conduit that supplies compressed air. This passage may be controlled by a throttle-valve of any suitable construction, that shown in the drawings consisting of a plunger H, arranged in an opening which intersects the supply-passage g and having a reduced part or neck h, a spring

h', whereby the plunger is normally shifted lengthwise, so that its full part closes the supply-passage, and a trigger or thumb-piece h², whereby the plunger may be shifted to bring its contracted part in line with the supply-passage for opening the same and admitting air into the distributing-chamber.

The valve mechanism for alternately admitting the compressed air and exhausting the spent air from opposite ends of the cylinder for causing the piston to reciprocate therein is constructed as follows: Within the rear or lower section of the valve-chest is formed a valve-chamber composed of a large upper or front part I and a small-lower or rear part I'. The side walls of the upper and lower parts of the valve-chamber are constructed to form cylindrical valve-seats, which are preferably axially in line or parallel with the axis of the power-cylinder. The top or outer end of the large valve-chamber is formed by the upper or front section of the valve-chest, while the bottom of the lower chamber is formed by the solid lower part of the lower section. The distributing-valve, which reverses the connection of the ports leading to opposite ends of the power-cylinder, consists of a large-area valve-piston J, arranged in the upper or large part of the valve-chamber, and a small-area valve-piston J', arranged in the lower or small part of the valve-chamber and connected with the large-area valve-piston by a contracted neck or reduced part j. The compressed air is preferably conducted to the lower end of the small part of the valve-chamber by a plurality of passages k, each of which consists of a longitudinal part extending from the distributing-chamber downwardly through both valve-chest sections outside of the valve-chamber, and a transverse part extending from the lower end of the longitudinal part to the lower end of the valve-chamber. The inner or lower ends of the several passages k all terminate in a main port k', which opens upwardly into the central part of the valve-chamber at the lower end thereof. That part of the bottom of the valve-chamber around the lower central air-inlet forms an annular shoulder with which the marginal part of the lower end of the distributing-valve engages 100

in the lowered position of the same. A short distance above the lower end the small part of the valve-chamber is provided with an annular reversing-port *l*, which is connected by a plurality of oblique reversing-passages *L* with the upper end of the power-cylinder. These passages open through the lower side of the valve-chest, so as to connect the port *l* directly with the upper end of the cylinder 5
 10 and serve alternately as air-supply conduits and as exhaust-conduits for this end of the power-cylinder. Above the port *l* the small part of the valve-chamber is connected with the atmosphere by a plurality of exhaust-passages *m*, each of which consists of a transverse part arranged in the lower section of the chest and opening at its inner end into the small part of the valve-chamber, and a longitudinal part extending from the outer end of 15
 20 the transverse part through the side of the lower chest-section and the power-cylinder and opening into the atmosphere adjacent to the lower end of the cap, as shown in Fig. 1.

In the elevated position of the distributing 25 or reversing valve (shown in Fig. 1) its lower piston is arranged between the inner end of the exhaust-ports *m* and the reversing-port *l*, whereby the passages *k* and *L* are connected, and compressed air is conducted into the upper 30 per end of the power-cylinder for propelling the piston downwardly or forwardly with a working stroke. In the depressed position of the reversing-valve (shown in Fig. 2) its lower or small piston is arranged below the 35 reversing-port *l*, whereby the passages *L* are connected with the exhaust-passages *m*, and the spent air in the upper end of the cylinder is permitted to vent into the atmosphere during the subsequent upward or idle return 40 stroke of the piston.

While the piston is moving forward or downward with a working stroke the air in front of the same is freely displaced into the atmosphere through the exhaust-passages *N* 45 *N'*. The exhaust-passage *N* has a port *n*, which opens into the lower part of the power-cylinder at a distance from its lower end, while its outer end opens into the atmosphere, preferably by communicating with one of the 50 exhaust-passages *m*. The exhaust-passage *N'* communicates at its lower end with the extreme lower end of the power-cylinder by a port *n'*, while its upper end connects with the upper large part of the valve-chamber by a 55 port *n''*, which opens through the lower part of the large cylindrical valve-seat thereof. During the descent of the piston while the reversing-valve is elevated, as shown in Fig. 1, part of the air below the same is expelled directly to the atmosphere through the exhaust 60 port and passage *n N* and part of it indirectly to the atmosphere by passing successively through the port *n'*, passage *N'*, port *n''*, upper and lower parts *I I'* of the valve-chamber, 65 and exhaust-passages *m*. The port *n* of the

exhaust-passage is so located that the same is covered by the piston during the last part of its downward or forward stroke, whereby the final portion of the air below the piston is expelled from the power-cylinder solely through the reversing-passage *N'* and exhaust passages and ports connected therewith and prevents cushioning of the blow of the piston against the tool. 70

When the piston reaches the lower end of its working stroke, its rear end has passed below a reversing-port *o*, which connects by a passage *o'* with a port *o''*, opening into the top of the upper large part of the reversing-valve chamber, this passage being formed partly in the cylinder and the two sections of the valve-chest, as shown. The instant the piston uncovers the reversing-port *o* the compressed air passes from the cylinder upwardly through passage *o'* and into the upper large part of the valve-chamber and exerts a downward pressure against the top of the upper valve-piston. Inasmuch as the pressure of the air against the top of the large-area valve-piston preponderates over the air-pressure against the under side of the small-area valve-piston, these pistons are shifted from the elevated position shown in Fig. 1 to the depressed position shown in Fig. 2. When this occurs, the connections of the compressed air and the exhaust-air are reversed for causing the piston to be raised by admitting compressed air underneath the piston and exhausting the spent air above the piston into the atmosphere. For this purpose air inlet and exit ports *p p'* are provided, which open through the upper part of the large cylindrical piston-valve seat, preferably on diametrically opposite sides thereof, and connect, respectively, with one of the air-passages *k* and the passage *N'*. 100 105

When the reversing-valve is in its depressed position, the compressed air passes from one of the passages *k* through the inlet-port *p*, thence across the valve-chamber above the upper valve-piston, thence out through the outlet-port *p'* into the passage *N'*, and thence into the lower end of the cylinder, thereby lifting or moving the piston therein with a return stroke. The full force of the compressed air is directed against the piston during the first part of its return or upward movement. The instant, however, that the piston has moved backwardly or upwardly sufficiently to uncover the exhaust-port *n* the force of the compressed air, leading to this end of the power-cylinder, is weakened to such an extent that the compressed air, which constantly presses upwardly against the small-area valve-piston, now preponderates over the downward pressure exerted against the large-area valve-piston, whereby the reversing-valve is shifted from the depressed position shown in Fig. 2 to the elevated position shown in Fig. 1. During the first part of the upward movement of the piston the air in the upper 110 115 120 125 130

part of the cylinder is expelled through the passages L , port l , and passages m ; but during the last part of this movement the compressed air enters the upper end of the cylinder, owing 5 to the reversal of the valve, thereby causing the piston to be cushioned at the end of its upward movement and avoiding jarring of the hands of the operator who is holding the tool. When the valve has been thus reversed, the 10 operation of the parts is repeated continuously in the manner before described while the throttle-valve is open.

By forming an annular shoulder at the bottom of the valve-chamber around the central 15 air-inlet the area of the lower end of the small valve-piston which is exposed to the air-pressure is less than when the valve is slightly raised, thereby enabling the valve to be held securely in its lowered position and permitting 20 the piston to complete its downward stroke and deliver an effective blow, but permitting the valve to be reversed quickly an instant after the same has started in its upward movement.

25 The valve-pistons are preferably constructed in the form of cups, the lower small one opening downwardly and the upper large one opening upwardly. By this construction of the reversing-valve the compressed air entering 30 the lower end of the valve-chamber centrally through the main port h' and air entering the upper end of the valve-chamber through the port o' is caused to spread uniformly over the entire area of these pistons and move the 35 same up or down in a straight line without any tendency to tilt the same, which would cause the valve to wear unnecessarily and also reduce the efficiency of the hammer.

By arranging the outlets of the exhaust- 40 passages adjacent to the lower end of the cap the same are not liable to be closed by the hand of the operator and cause interference with the working of the hammer, nor is the workman so liable to be spattered with oil or 45 other material which may be ejected by the blast of the escaping air, as would be the case if the exhaust-outlet were in the cap.

By making the upper seat of the reversing- 50 valve wholly in the lower section of the valve-chamber the upper valve-piston can be ground more accurately to its seat.

In order to prevent the reversing-valve from getting stuck on the dead-center by grit or other impurities in the air, and thus leaving 55 the tool in a balanced and inoperative condition, one or more springs q are provided, which tend constantly to move the reversing-valve toward one end of its stroke. As shown in Figs. 1 and 2, these springs are arranged between the upper valve-piston and the top of 60 the valve-chamber and operate to hold the reversing-valve yieldingly in its lower position. In this position of the reversing-valve the ports are so connected that air is admitted to 65 the lower end of the cylinder for beginning

the operation of the piston with a backward stroke. By means of these springs the valve can never become stuck at a place where it is about to reverse the air connections of the cylinder, thereby avoiding loss of time incident to adjusting tools as ordinarily constructed in which this difficulty frequently occurs. The reversing-port o' at the upper end of the valve-chamber is made somewhat smaller than the port p' , so that the air entering through 70 the inlet-port p and moving in the direction of least resistance will favor the port p , from which latter the air passes to the cylinder underneath the piston, thereby preventing the air from being lead backwardly through the 75 port o' and passage o into the cylinder above the piston and balancing the pressure on the piston.

For continuously supplying lubricant to the hammer whenever the same is in operation 80 lubricating means are provided which are operated automatically and are controlled by the working parts of the hammer, such as the reversing-valve or the piston. The preferred means for this purpose (shown in the drawings) comprises a reservoir or chamber R , arranged in the upper section of the valve-chest and having an open top through which the same is filled with lubricant, such as oil or grease, this opening being normally closed by 85 a screw plug or cover r . In its bottom the reservoir is provided with a discharge-opening s , which leads into the upper end of the valve-chamber and which is constructed at its upper end to form a conical valve-seat. T 90 represents a conical feed-valve arranged in the reservoir and movable axially toward and from the seat in the opening s for controlling the discharge of lubricant. This lubricating-valve is moved downward against its seat for 95 closing the opening s by means of a spiral spring t , seated at its opposite ends on a boss t' , formed on the upper end of the oil-valve, and a similar boss t'' , formed on the under side of the reservoir-cover. The lubricating- 100 valve is provided at its lower end with a depending stem which projects downwardly into the reversing-valve chamber. On the upper side of the reversing-valve is arranged a tappet u , which is adapted to engage the lower 105 end of the stem of the lubricating-valve and lift the latter from its seat during every upward movement of the same and leaves said stem to permit the lubricating-valve to engage its seat during each downward movement of the reversing-valve. By this means 110 the lubricating-valve is momentarily opened during every reciprocation of the reversing-valve, and small quantities of oil are continuously supplied to the working parts of the 115 hammer, thereby insuring positive and uniform lubrication thereof with a minimum amount of oil. The tappet u preferably consists of a screw which engages with a threaded opening in the large-area valve-piston and 120

has its head arranged in the neck of the reversing-valve, which is made hollow for this purpose. By constructing the tappet in the form of a screw the same can be readily adjusted for regulating the amount of oil, which is supplied intermittently, and the wear upon the parts may also be conveniently taken up.

I claim as my invention—

1. A pneumatic hammer comprising a power-cylinder, a valve-chest having an integral bottom and a separable top and containing a valve-chamber having a large upper cylindrical valve-seat, a small lower cylindrical valve-seat, a lower main air-inlet port opening centrally into the lower end of said chamber, an annular shoulder formed at the lower end of said chamber around said central inlet-port thereof, an intermediate main air-inlet port opening into the small valve-seat above said lower central inlet-port and connected by oblique passages with the upper end of the cylinder, an exhaust-passage opening into the lower valve-seat above said intermediate port, an upper main air-inlet port connecting the upper part of said large valve-seat with the air-supply, another upper main air-inlet port connecting the upper part of said large valve-seat with the lower end of said cylinder and an upper exhaust-port connected with the lower part of said large valve-seat, and an imperforate main distributing-valve arranged in said chamber and having a lower small valve-piston constructed in the form of a downwardly-opening cup and coöperating with said small valve-seat for connecting said main lower air-inlet port either with the main intermediate air-port or with said lower exhaust-port and having the marginal part of its lower end constructed to bear against said annular shoulder, and an upper large valve-piston constructed in the form of an upwardly-opening cup and coöperating with said upper large valve-seat for connecting said main upper air-inlets or said upper and lower exhaust-ports, substantially as set forth.

2. A pneumatic hammer comprising a power-cylinder, a valve-chest containing a valve-chamber and ports for connecting opposite ends of said cylinder with the air-supply and with the atmosphere, a valve controlling said ports, and a spring bearing constantly against the valve and operating to yieldingly hold said valve at one end of its movement, substantially as set forth.

3. A pneumatic hammer comprising a

power-cylinder, a valve-chest having a chamber containing a large upper cylindrical valve-seat, a small lower cylindrical valve-seat and ports connecting opposite ends of the cylinder with an air-supply and with the atmosphere, a valve controlling said ports and having a large upper valve-piston which coöperates with said upper valve-seat for controlling the admission and exhaust of air from the lower end of the cylinder, and a lower small valve-piston which coöperates with the lower valve-seat for controlling the admission and exhaust of air from the upper end of the cylinder, and a spring bearing constantly at its opposite ends against the upper end of said valve and the top of the valve-chamber and operating to hold the valve yieldingly in its depressed position, substantially as set forth.

4. A pneumatic hammer comprising a power-cylinder, means for controlling the air connections with said cylinder comprising a valve-chamber and a distributing-valve reciprocating in said chamber, an oil-reservoir having an outlet which opens into the top of said chamber, and a lubricator-valve which controls said outlet-opening and which is engaged by the upper end of said distributing-valve during every upward stroke of the same for lifting the lubricator-valve from its seat, substantially as set forth.

5. A pneumatic hammer comprising a power-cylinder, a piston, a valve-chest having a valve-chamber in its lower part, a lubricator-reservoir in its upper part and a lubricator-discharge opening arranged in the bottom of the reservoir and opening into said chamber, an air-distributing valve arranged in said chamber and operating to connect the opposite ends of said cylinder alternately with the air-supply and with the atmosphere, a lubricator-valve coöperating with a seat in said discharge-opening for controlling the escape of lubricant from the chamber and having a stem at its lower end and a boss at its upper end, a cover applied to said reservoir and having a boss on its under side, a spring fitted at its ends on the bosses of said lubricator-valve and cover, and a tappet coöperating with the stem of said lubricator-valve for opening the same and consisting of a screw arranged on the air-valve, substantially as set forth.

Witness my hand this 9th day of April, 1904.
